SPOON OR SIMILAR ARTICLE

Ellen B. Manderfield, Syracuse, N.Y., assignor to Oneida Ltd., Oneida, N.Y., a corporation of New York

Filed Mar. 5, 1965, Ser. No. 84,101

Term of patent 14 years

(Cl. D54—12)

FIG. 1

FIG. 2

FIG. 3

FIG. 4

FIG. 5

FIG. 6

FIG. 1 is a front elevational view of a spoon, showing my new design;

FIG. 2 is a back elevational view of the spoon;

FIG. 3 is a side elevational view of the spoon; and

FIGS. 4, 5 and 6 are enlarged sections on the respective lines 4—4, 5—5 and 6—6 of FIG. 1.

The essential features of my design for a spoon or similar article reside in the configuration of the handle in combination with the particular type of ornamentation as applied thereto.

I claim:

The ornamental design for a spoon or similar article, substantially as shown and described.
